UNITED STATES PATENT OFFICE.

ALFRED B. FOWLER, OF EXETER, NEW HAMPSHIRE, ASSIGNOR TO OLIVER A. MILLER, OF BROCKTON, MASSACHUSETTS.

BOOT-TREEING MACHINE.

SPECIFICATION forming part of Letters Patent No. 393,003, dated November 20, 1888.

Application filed June 26, 1888. Serial No. 278,252. (No model.)

To all whom it may concern:

Be it known that I, ALFRED B. FOWLER, a citizen of the United States, and a resident of Exeter, in the county of Rockingham and State of New Hampshire, have invented new and useful Improvements in Treeing Machines, of which the following, taken in connection with the accompanying drawings, is a specification.

This invention relates to improvements in machines for treeing boots or shoes, and it is carried out as follows, reference being had to the accompanying drawings, wherein—

Figure 1 represents a central longitudinal section of the machine, showing one of the trees and its shoe in elevation. Fig. 2 represents a horizontal section on the line A B in Fig. 1, as seen from below said line; and Fig. 3 represents a similar section on said line A B, as seen from above such line. Fig. 4 represents a detail sectional view of the automatic expansion device for the tree; and Fig. 5 represents an end view of the same, as seen from Z in Fig. 4. Fig. 6 represents a detail sectional view of the treadle-locking mechanism.

Similar letters refer to similar parts wherever they occur on the different parts of the drawings.

The frame or standard of the machine is preferably made in two parts—namely, a lower one, *a*, adapted to rest on the floor, and an upper one, *b*, that is made vertically adjustable within the upper end of the lower one, as shown in Fig. 1, so as to enable the machine to be raised or lowered to suit the requirements of the operator, and after such upper frame part is adjusted relative to the lower one it is secured to the latter by means of screws or other suitable fastening device.

To the upper end of the frame or standard *b*, I secure an annular ring, *c*, having at one place of its interior portion a recess, *c'*, (shown in Figs. 1 and 2,) for a purpose, as will herein-after be described.

c' is the central hub of the ring *c*, and to it is secured the vertical pin or shaft *C*, on which is journaled the tree-carrying head *D*, as shown in Figs. 1 and 2, which head is provided with two or more radially-projecting sockets, *d d*, for receiving the shanks of the boot-trees, as shown in Figs. 1, 2, and 4.

On the circumference of the head *D*, between its sockets *d*, are made vertical notches or locking-recesses *d' d'*, adapted to receive the upper end of the spring-pressed locking-rod *e* that is guided in a bearing on the ring *c* or other stationary part of the machine, as shown in Figs. 3 and 6, and normally held upward in a locked position relative to the head *D* by the influence of a spring, *E*, or equivalent device. To the lower end of the rod *e* is adjustably secured the downwardly-projecting rod *e'*, the lower end of which is connected to the treadle-lever *f*, that is pivoted at *f'* to the frame or standard *a*. By depressing the treadle-lever *f*, the rod *e* will be drawn downward against the influence of the spring *E* sufficiently to cause its upper end to be disengaged from that one of the locking-notches *d'* in the head *D*, in which it was locked, when the said head with its trees and shoes held thereon may be turned freely around a part of a revolution until the next locking-notch, *d'*, in the series reaches the locking-rod *e*, when the latter will automatically be forced upward into such notch by the influence of the spring *E*, the operator in the meantime having removed his foot from the treadle-lever *f*, and so on.

In connection with the machine I use a number of boot-trees equal in number to the sockets *d* in the head *D*. Each of these trees is of the usual expandable construction and need not here minutely be described, it being sufficient for the purpose to state that *g* represents the tree-body provided with a cylindrical shank, *g'*, loosely inserted in the socket *d* of the head *D*, in which it may be turned around during the operation of the machine. A setscrew, *d''*, screwed through the socket *d* and having its inner end projecting in an annular groove, *g''*, on the shank *g'*, serves to connect the latter to the said socket *d*, as shown in Figs. 1 and 4. *g'* is the usual forward part of the tree, secured to or forming a part of the body *g*, and *g''* is the expandible back part of the tree, as usual.

The back portion, *g'*, is actuated to and from the front portion, *g''*, by means of the rod *g'*, arranged within the tree, as usual, and connected in its outer end to a slotted link, *g''*, or equivalent device, pivoted to the part *g'* or its connections, said rod *g'* being automatically forced

outward by the influence of a spring, g^7 , (shown in Figs. 1 and 4,) to move the part g^4 toward the part g^3 to enable the finished boot or shoe to be removed from the tree and to place another one thereon.

I wish to state that I do not claim the expansive tree, as shown, nor the mechanism, as described, for its operation as my invention, as such is well known in the art, and any of the usual expansive trees may be used with my machine without departing from the essence of my invention.

In connection with the expansive trees I use an automatic mechanism for expanding and contracting them during the intermittent rotary motion of the head D, and it is constructed as follows:

To the inner end of each expansion-rod g^5 is secured, in a suitable manner, a spindle, I, arranged within a recess, h'' , in the block H, to the lower portion of which is journaled the roller h on a pin, h' , as shown in Figs. 1, 2, 3, and 4. The said roller h is automatically forced outward against the interior of the ring e by the influence of the spring g^7 on the expansion-rod g^5 , as shown in said Figs. 1, 2, 3, and 4. During the operation of the machine the operator stands at the place marked Y in Fig. 2, and an attendant stands at the place marked X in the said figure.

The boot-tree opposite to X is automatically contracted by the roller h being forced into the recess e' on the interior of the cylindrical ring e by the influence of the spring g^7 , as shown in Figs. 1, 2, 3, and 4, thus enabling the attendant at X to remove the finished shoe and to place another one on the tree.

The operator at Y in the meantime performs the treeing operation on the boot or shoe directly in front of him, the head D during such operation being locked firmly in position to the frame or standard of the machine by the locking mechanism hereinabove described.

The boot-tree at Y, as well as all the other trees in the series except the one at X, is automatically expanded by the rods g^5 being moved toward the center of the ring e by the agency of the rollers h riding and resting on the cylindrical interior surface of the ring e , as shown in Figs. 1, 2, and 3, by which the boots or shoes on such expanded trees are properly stretched on the latter. When the operator at Y has treed the boot or shoe in front of him, he depresses the treadle f , and thus liberates the head D from the standard and swings said head and its trees a partial revolution in the direction shown by arrows in Figs. 2 and 3, until the next tree in the series is brought opposite to him, when the head D is again locked in position, another boot treed, and the finished boot at X removed by the attendant and replaced by another one to be treed, and so on; but it is desirable that during the treeing operation any stretching of the leather that may occur should be automatically taken up; and for this purpose I interpose between the bottom of the recess h'' in the block H and a

collar, i , on the spindle I a coiled or rubber spring, i' , (shown in Figs. 1 and 4,) the said collar i being held in position on the spindle I by means of a key, i'' , passing through a slot, i'' , in the spindle I, as shown in Figs. 1 and 4.

The tension of the spring i' is regulated by means of a set screw, i^4 , screwed through the end of the spindle I against the key i'' , as shown in said figures.

h is a ring secured to the rear of the block H, and it has on the top an opening, k' , of a size sufficient to enable the key i'' to pass through it, by which arrangement the tree may be removed, when so desired, simply by unscrewing the set-screw i^4 and introducing a hook or other suitable or convenient tool through one of the perforations d^3 in the head D, and by this means withdrawing the said key i'' from the slotted spindle I. The ring h serves to prevent the key i'' from dropping out of the slotted spindle I during the rotation of the tree around its axis while the treeing process takes place.

Having thus fully described the nature, construction, and operation of my invention, I wish to secure by Letters Patent and claim—

1. In a boot or shoe treeing machine, a stationary hollow base, a , and a vertically-adjustable non-rotating standard, b , in combination with a rotary head, D, and a series of rotary boot or shoe trees journaled in said head, substantially in a manner and for the purpose set forth.

2. In a boot or shoe treeing machine, a stationary ring, c , having on its interior portion a recess, c' , combined with a tree-carrying head, D, pivoted to said ring or its connections, and a series of expansive boot-trees journaled in sockets on said heads and having their spring-pressed expansion-rods connected to rollers adapted to be actuated by said ring for the purpose of automatically expanding and contracting the trees, substantially as and for the purpose set forth.

3. In a boot or shoe treeing machine, the stationary ring c , having on its interior the recess c' , and the rotary head D, having journaled to it a series of expansive trees with spring-pressed expansion-rods g^5 , combined with the blocks H, yieldingly and adjustably secured to said expansion-rods and provided with rollers h , adapted to lie in contact with and to be actuated by the ring c and its recess c' , substantially in a manner and for the purpose set forth.

4. In a boot or shoe treeing machine, a standard or frame, a cam-shaped ring secured to it, a rotatable head journaled to said ring or standard, a locking device for securing said head and standard or ring together, and a series of expansive trees journaled to said head, and means, substantially as described, for automatically expanding and contracting the boot-trees during the rotation of the tree-carrying head, substantially as and for the purpose set forth.

5. In a boot or shoe treeing machine, a sta-

tionary cam-shaped ring, *c c'*, a boot-tree-carrying head, *D*, journaled to said ring or its connections and having perforations *d*³, as described, combined with the expansive trees *s* journaled to said head and having their spring-pressed expansion-rods *g*⁵ connected to spring-pressed spindles *I*, arranged within recesses in the roller-carrying blocks *H*, the slotted rings *k k'*, secured to said blocks *H*, and the set-screws *i'* for regulating the tension of the springs *i''*, and the keys *i'''*, all arranged and

combined substantially as and for the purpose set forth.

In testimony whereof I have signed my name to this specification, in the presence of two subscribing witnesses, on this 23d day of June, A. D. 1888.

ALFRED B. FOWLER.
